Patented Sept. 28, 1976

241,600

COMBINED FOOD STORAGE CONTAINERS AND CARRYING HANDLE

Harold P. Ashton, Providence, R.I., assignor to Dart Industries, Inc., Los Angeles, Calif.

Filed Mar. 21, 1975, Ser. No. 560,468

Term of patent 14 years

Int. Cl. D7—06

U.S. Cl. D7—76

FIG. 1

FIG. 2

FIG.5

FIG. 1 is a top perspective view of combined food storage containers and carrying handle showing my new design;

FIG. 2 is a front elevational view thereof;

FIG. 3 is a side elevational view thereof;

FIG. 4 is a top plan view thereof; and

FIG. 5 is a bottom plan view thereof.

I claim:

The ornamental design for combined food storage containers and carrying handle, substantially as shown.
